CLAIM

The ornamental design for a toy block incorporating a seat and table for children, as shown and described.

DESCRIPTION

FIG. 1 is a perspective view showing my new design for a toy block incorporating a seat and table for children; FIG. 2 is an exploded perspective view thereof; FIG. 3 is a perspective view of the ABC component of the design, shown separately for clarity; FIG. 4 is a perspective view of the opposite side of FIG. 3; FIG. 5 is perspective view of the 123 component of the design shown separately for clarity; FIG. 6 is a perspective view of the opposite side of FIG. 5; FIG. 7 is a perspective view showing the components of the design in an alternate orientation; FIG. 8 is a perspective view showing the components of the design in a further alternate orientation; FIG. 9 is a top plan view of one component of the design, the top views of both components being the same; and, FIG. 10 is a front elevational view of one component of the design, the front views of both components being the same.
